UNITED STATES PATENT OFFICE.

HERMAN FUCHS, OF ST. LOUIS, MISSOURI.

VALVE-CAP.

1,271,695.

Specification of Letters Patent.

Patented July 9, 1918.

Application filed November 18, 1916. Serial No. 131,502.

To all whom it may concern:

Be it known that I, HERMAN FUCHS, a citizen of the United States, residing at St. Louis, in the State of Missouri, have invented new and useful Improvements in Valve-Caps, of which the following is a specification.

The present invention relates to a combined valve cap and plug primarily adapted for use in connection with pneumatic tires and the like, and comprehending particularly improvements upon the cap shown in my prior application, Serial No. 79,185, filed February 18, 1916.

15 The invention resides in the provision of a cap having integrally formed therewith an axial plug adapted when the cap is assembled on the valve stem to tightly fit within the port of the stem, thus assuring 20 against any accidental leakage of air from the tire through the port of the said stem.

Furthermore, I aim to provide the plug of a cap with a cavity formed in the closed end of the bore thereof, whereby when the 25 cap is in assembled position, will clear the valve plunger and prevent the unseating of the valve.

A still further object of the invention is to provide within the bore of the plug a 30 packing, adapted when the plug is mounted within the valve stem, to engage with the valve seat which when the valve plunger is threaded into the cavity of the plug, the packing will first engage with the valve 35 seat of the inside tube valve.

With the above and other objects in view, the invention consists in the novel features, details of construction and combination of parts which will hereinafter be more fully 40 set forth, illustrated in the accompanying drawing and pointed out in the appended claims.

Figure 1 is a vertical sectional view taken through the cap and plug illustrating one 45 form of my invention;

Fig. 2 is a view similar to Fig. 1, illustrating a slight modified form of cap;

Fig. 3 is a vertical section taken through the valve cap and stem, showing the form 50 of cap illustrated in the preferred form of the invention as applied to the valve stem for use.

Fig. 4 is a vertical section taken through the valve cap and stem showing a modified 55 form of cap applied to the valve stem for use;

Fig. 5 is a vertical sectional view taken through the cap and plug, showing a still further modified form of invention; and

Fig. 6 is a vertical sectional view taken 60 through the cap and plug, showing a still further modified form of invention.

With reference to the accompanying drawing, the character 5 denotes a portion of a valve stem in use upon a pneumatic tire 65 and as no claim is made to this particular form of valve stem, it is not thought necessary to further describe the same.

In all forms of the invention, there is shown a valve cap 6 provided with a substantially cup-shaped body portion 7 of hollow tubular formation, and formed with a closed end 8. Formed integral with the cap on the closed end 8 of the cup-shaped body portion 7 thereof, is an axially arranged 75 plug 9 provided with a centrally located bore 10, the closed end of the bore 10 being internally threaded and extended within the closed end 8, to provide a cavity 11 adapted upon the mounting of the cap 6 80 upon the stem 5, to receive the threaded extremity 12 of the valve plunger 13. The said plug is of hollow tubular form, and arranged in spaced concentric relation with the inner circumference of the cup-shaped 85 body 7 of the valve, to provide the valve with an annular socket 14 in which is inserted a packing gland 15, said gland embracing the plug 9 and engaging with the closed end 8. Screwing the cap upon the 90 stem will cause the said gland to contact with the upper edge of the valve stem and cause an air-tight connection between the said cap and stem.

Reference being had now more particularly to the forms of invention disclosed in Figs. 1 and 3 of the drawing, the lower end of the cup-shaped body portion 7 terminates below the lower end of the cup of the plug 9 and is exteriorly threaded as at 16, to permit of the collar 17 to threadedly connect with said cup, all of which being clearly shown in Fig. 3 of the drawing. This collar is identical in construction with that disclosed in the prior pending application 105 above referred to, therefore a further description of the function and structure of the collar is believed to be unnecessary. The plug is exteriorly threaded as at 18, whereby the same may be screwed into the port 19 110 of the valve stem 5. It will be obvious from the disclosure that when the plug is thread-

ed into the bore of the valve stem, the cap loosely fits around the outer circumference of the stem, thus assuring against any difficulties being experienced in removing the 5 cap from said stem, and the air-tight connection between the cap and valve stem is caused by the threading of the collar 17 on the exteriorly threaded lower end 16 of the cup-shaped body portion 7.

10 The specific form of cap and plug illustrated in Figs. 1 and 3 of the drawing, and furthermore which is the preferred form of the invention, is adaptable for use on the Schraeder type of tire valve stem.

15 The modified form of invention shown in Figs. 2 and 4 of the drawing illustrates the outer periphery of the lower end of the cup-shaped body portion 7 unthreaded and is used on valve stems without the employment 20 of the collar 17. In the form of the invention shown in Fig. 5 of the drawing the bore of the plug has seated therein a packing sleeve 20 which is of a length greater than the length of the bore 10 of 25 the plug, providing the same with a protruding extremity 21, whereby upon the screwing of the plug within the bore of the valve stem, the protruding extremity 21 of the packing will first engage with the valve 30 seat 22 previous to the screwing action of the exteriorly threaded end in the interiorly threaded cavity 11.

The further modified form of invention illustrated in Fig. 6 of the drawing shows 35 the cup-shaped body portion 7 as interiorly threaded, denoted by the reference character 24 adapted to threadedly connect the cap to the exteriorly threaded portion of the stem, for the reason that the cup body in this particular instance is shown with the exterior 40 threads omitted therefrom. A packing

sleeve 25 is mounted within the bore of the plug and performs the same function as that stated for the packing sleeve 20.

From the foregoing description, taken in 45 connection with the accompanying drawing, the advantages of construction and the method of operation of the invention will be readily apparent to those skilled in the art to which the invention relates, and while 50 I have described the principles of operation of the invention, together with the device which I now consider to be the best embodiment thereof, I desire to have it understood that the device shown is merely illustrative, 55 and that such changes may be made when desired as are within the scope of the appended claims.

What is claimed as new, is:—

1. In combination with a valve stem, a 60 cap comprising an externally threaded cup portion slidably engageable upon the valve stem, a gasket within said cup portion engageable upon the end of the stem, a metallic sleeve threaded upon the valve stem and 65 having an internally threaded flange engaged upon the exterior of the cap, and a gasket between said sleeve and the end of said cup portion.

2. In combination with a valve stem, a 70 cap comprising a cup portion disposable externally upon the valve stem, a concentric externally threaded plug portion engageable within the valve stem and provided 75 with a bore terminating in a recess receiving the valve plunger, and a tubular gasket within said bore and extending beyond the end of said plug for engagement with the valve seat within the stem.

In testimony whereof I affix my signature. 80

HERMAN FUCHS.
